CARRYING CASES

Robert C. Casselman, Auburndale, Mass., assignor to Polaroid Corporation, Cambridge, Mass., a corporation of Delaware

Application January 9, 1953, Serial No. 330,459

11 Claims. (Cl. 150—52)

This invention relates to carrying cases and more particularly to cases for carrying cameras and/or photographic accessories such as film, flash guns, flash bulbs, exposure meters and the like.

An object of the invention is to provide an improved carrying case of the above type which, through the use of a novel arrangement and coaction of fixed and detachable strap guides and an endless carrying strap, permit the carrying case to be converted from a hand-carried case to one which may be worn suspended from a shoulder of the wearer.

Other objects of the invention will in part be obvious and will in part appear hereinafter.

The invention accordingly comprises an article of manufacture possessing the features, properties, and relation of elements which will be exemplified in the article hereinafter described and the scope of the application of which will be indicated in the claims.

For a fuller understanding of the nature and objects of the invention, reference should be had to the following detailed description taken in connection with the accompanying drawings wherein:

Figure 1 is an end view of the carrying case of the invention showing the carrying strap arranged for hand carriage;

Fig. 2 is a front view of the carrying case shown in Fig. 1 but showing the strap arranged for shoulder carriage;

Fig. 3 is a plan view of the carrying strap of the invention; and

Fig. 4 is a front view of a modification of the carrying case of the invention.

In the drawing, wherein like reference numerals denote like elements throughout the several views thereof, 10 represents generally a carrying case having a front wall 12, a rear wall 14, side walls 16 and 18, a bottom or base 20, and a top wall or cover 22 which is longer than the front-to-back dimension of the case so that the portion which extends beyond the front wall comprises a flap 24. The lower central section of flap 24 is provided with a tab 26 having a latch means 28 which is adapted to engage a cooperating latch means 30 affixed to the front wall 12, thereby enabling the carrying case to be locked. Suitable foot members 32, which may be of metal, hard rubber or plastic material, are positioned adjacent each corner of the base 20 to provide a rest for the carrying case.

Fixedly secured to the upper portion of rear wall 14 are a pair of guide members 34, for example of leather (one only of which is shown in Fig. 1). A pair of guide members 36, for example of metal, are fixedly secured to the base 20 substantially at the extremity thereof adjacent front wall 12 and in positions such that one guide member 36 is in alignment with one of guide members 34 while the other of guide members 36 is in alignment with the other of guide members 34.

A third pair of guide members 38, which may be of leather or a suitable resilient plastic material, are se-

cured to the front wall 12 in positions such that one member 38 is in alignment with one of each of members 34 and 36 while the other member 38 is in alignment with the other of each of members 34 and 36. One end 5 of each of guide members 38—preferably the inner end thereof—is fixedly secured to front wall 12 by means of stitching 40 or other permanent fastening means such as rivets, staples and the like. The other end of each guide member 38 is detachably secured to the front wall 12 by such means as snap fasteners 42.

The endless carrying strap of the invention, which may be formed of leather, rubber, plastic materials or the like, is shown at 44 in Fig. 3 as comprising two elongated sections 46 and 48 and two short sections 50 and 52, the center of each of the latter portions being provided, respectively, with grip portions 54 and 56. Detachably secured to grip portion 54 is a leather keeper member 58 which is provided with snap fastener means 60 and which is adapted to encompass either grip portion 54, alone, or both of grip portions 54 and 56, depending on whether the strap is in the position shown in Fig. 2 or Fig. 1, respectively.

When the carrying case of the invention is assembled during manufacture, the endless carrying strap is slidably associated therewith by means of the guide members 34, 36 and 38. Specifically, elongated section 46 is attached to the carrying case by means of the guide members 34, 36 and 38 on the right-hand portion of the case, as viewed in Fig. 2, while elongated section 48 of the strap is similarly attached to the carrying case by means of the guide members 34, 36 and 38 on the left-hand portion of the case. The strap is thus fixedly secured by means of the pair of fixed guide members 34 on rear wall 14 of the case and by the pair of fixed guide members 36 on the base thereof and is detachably secured to front wall 12 of the carrying case by means of the pair of detachable guide members 38.

The carrying strap is slidable in the fixed guide members 34 and 36, the sections 46 and 48 of the strap being sufficiently long as to encompass the front, bottom and rear of the case and to extend beyond the top thereof, as shown in Fig. 1, where the two grip portions 54, 56 may be held together by means of the detachable keeper member 58. With the strap in the position shown in Fig. 1, the case is adapted for hand carriage.

By detaching from the front wall 12 of the case one end of each of guide members 38, as by disengaging the snap fasteners 42, the strap may be slidably moved through the fixed guide members 34 and 36, by exerting a pulling force on the grip portion 54, so that elongated sections 46 and 48 extend only under the base and up the rear wall 14 of the carrying case to a position well beyond the top wall or cover 22, as shown in Fig. 2. When thus positioned, it will be seen that section 52 of the strap extends between the pair of fixed guide members 36. The arrangement of the strap illustrated in Fig. 2 permits the case to be worn suspended from a shoulder of the wearer.

While the carrying case has been described as one particularly adapted for use as a container for a camera and/or photographic accessories, it should be understood that its utility is not limited to the photographic field. The principles of the invention may be equally applied to a lady's handbag, for example, in which embodiment the positions of the fixed strap guides 34 and the detachable strap guides 38 are reversed, i. e., the strap guides 38 are detachably secured to a rear wall 14 and strap guides 34 are fixedly secured (Fig. 4) to front wall 12. Guides 36 are then preferably affixed to the base 20 adjacent to the rear wall 14 of the case. When it is desired to hand-carry the handbag of this embodiment of the invention, the strap is allowed to remain in the position shown in Fig. 1. How-

3

ever, in order to convert the handbag to shoulder-carrying use, one end of each detachable strap guide 38 (not shown in Fig. 4) is disengaged from rear wall 14 and the strap slidably moved, through the fixed guide members 36 on the base and fixed guide members 34 on the front wall 12, by exerting a pulling force on grip portion 56, so that elongated sections 46 and 48 extend only under the base 20 and up the front wall 12 of the carrying case to a position well beyond the top wall or cover 22. In this embodiment, since section 50 of the strap, rather than section 52, extends between the pair of fixed metal guide members 36 on the base of the carrying case, keeper member 58 is preferably detachably secured to grip portion 56 rather than to grip portion 54.

In the just-described embodiment of the invention, it will be appreciated that whether the handbag is hand- or shoulder-carried, the elongated strap sections 46 and 48 extending up the front wall 12 would substantially prevent accidental opening of the flap 24 of the bag.

While strap guide members 34 and 36 have been described as being made, for example, of leather and metal, respectively, it should be understood that guides 34 could be formed from metal and guides 36 from leather, or both guides 34 and 36 could be leather or metal, or even a suitable plastic material.

It should further be understood that the keeper member 58, which may be formed from plastic materials or rubber rather than leather, may, if desired, be detached from the grip portion to which it is secured when the carrying case is worn suspended from a shoulder of a wearer.

Since certain changes may be made in the above article of manufacture and different embodiments of the invention could be made without departing from the scope thereof, it is intended that all matter contained in the foregoing description or shown in the accompanying drawings shall be interpreted as illustrative and not in a limiting sense.

What is claimed is:

1. A carrying case comprising a front wall, a rear wall, a base, a cover, a first pair of strap guide members fixedly secured to said base, a second pair of strap guide members fixedly secured to one of said front and rear walls, a third pair of strap guide members detachably secured to the other of said front and rear walls, and an endless carrying strap, said strap being slidably engaged by at least said first and second pairs of guide members.

2. A carrying case comprising a front wall, a rear wall, a base, a cover, a first pair of strap guide members fixedly secured to said base, a second pair of strap guide members fixedly secured to one of said front and rear walls, a third pair of strap guide members detachably secured to the other of said front and rear walls, and an endless carrying strap comprising two elongated sections and two short sections, said elongated sections being sufficiently long to encompass said front wall, said base and said rear wall and to extend beyond the cover of said carrying case, said strap being slidably engaged by at least said first and second pairs of guide members.

3. A carrying case comprising a front wall, a rear wall, a base, a cover, a first pair of strap guide members fixedly secured to said base, a second pair of strap guide members fixedly secured to one of said front and rear walls, a third pair of strap guide members detachably secured to the other of said front and rear walls, and an endless carrying strap comprising two elongated sections and two short sections, said elongated sections being sufficiently long to encompass said front wall, said base and said rear wall and to extend beyond the cover of said carrying case, said strap being slidably engaged by said first and second pairs of guide members and detachably engaged by said third pair of guide members.

4. A carrying case comprising a front wall, a rear wall, a base, a cover, a first pair of strap guide members fixedly secured to said base, a second pair of strap guide members fixedly secured to one of said front and rear walls, a third

pair of strap guide members detachably secured to the other of said front and rear walls, and an endless carrying strap comprising two elongated sections and two short sections, said elongated sections being sufficiently long to encompass said front wall, said base and said rear wall and to extend beyond the cover of said carrying case, said strap being slidably engaged by said first and second pairs of guide members and detachably engaged by said third pair of guide members, said third pair of strap guide members being adapted, when operatively secured to said other wall, to hold and guide said strap so as to render the carrying case suitable for hand carriage and, when inoperatively secured to said other wall, being adapted to render said case suitable for shoulder carriage.

15 5. A carrying case comprising a front wall, a rear wall, a base, a cover, a first pair of strap guide members fixedly secured to said base, a second pair of strap guide members fixedly secured to one of said front and rear walls, a third pair of strap guide members detachably secured
20 to the other of said front and rear walls, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of said first and second pairs of guide members and adapted to be detachably engaged by the other member of said third pair
25 of guide members, each of said short sections being provided with a grip portion, said third pair of strap guide members being adapted, when operatively secured to said other wall, to hold and guide said strap so as to render the carrying case suitable for hand carriage and, when
30 inoperatively secured to said other wall, being adapted to render said case suitable for shoulder carriage.

40 to render said case suitable for shoulder carriage.

6. A carrying case comprising a front wall, a rear wall, a base, a cover, a first pair of strap guide members fixedly secured to said base, a second pair of strap guide members fixedly secured to one of said front and rear walls, a third pair of strap guide members detachably secured to the other of said front and rear walls, and an endless carrying strap comprising two elongated sections and two short sections, one of said elongated sections being slidably engaged by one member of each of said 45 first and second pairs of guide members and adapted to be detachably engaged by one member of said third pair of guide members, the other of said elongated sections being slidably engaged by the other member of each of said 50 first and second pairs of guide members and adapted to be detachably engaged by the other member of said third pair of guide members, each of said short sections being provided with a grip portion, one of said 55 grip portions having detachably secured thereto a keeper member adapted to encompass at least said one of said grip portions, said third pair of strap guide members being adapted, when operatively secured to said other wall, to hold and guide said strap so as to render the carrying case suitable for hand carriage and, when inoperatively secured to said other wall, being adapted 60 to render said case suitable for shoulder carriage.

65 to render said case suitable.

70 7. A carrying case comprising a front wall, a rear wall, a base, a cover, a first pair of strap guide members fixedly secured to said base, a second pair of strap guide members fixedly secured to one of said front and rear walls, a third pair of strap guide members detachably secured to the other of said front and rear walls, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of

75 said first and second pairs of guide members and adapted

5
to be detachably engaged by the other member of said third pair of guide members, each of said short sections being provided with a grip portion, one of said grip portions having detachably secured thereto a keeper member adapted to encompass at least said one of said grip portions, said carrying case being characterized by the fact that it is adapted for shoulder carriage by disengaging the elongated sections of the strap from said third pair of guide members and exerting a pulling force on that short section to which said keeper member is secured, thereby causing said elongated sections to slidably move through said first and second pairs of guide members until the last-named short section is located beyond said cover by substantially half the length of one of said elongated sections and the other short section is located between each guide member of said first pair of guide members.

8. A carrying case comprising a front wall, a rear wall, a base, a cover, a first pair of strap guide members fixedly secured to said base, a second pair of strap guide members fixedly secured to said rear wall, a third pair of strap guide members detachably secured to said front wall, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of said first and second pairs of guide members and adapted to be detachably engaged by the other member of said third pair of guide members, each of said short sections being provided with a grip portion, said elongated sections being long enough to extend completely around the case through said guides so as to permit the grip portion of said short sections to be in engagement with one another, that grip portion forming part of the short section joining the extremities of the elongated sections slidably associated with said rear wall having detachably secured thereto a keeper member adapted to encompass said grip portions, said carrying case being characterized by the fact that it is adapted for shoulder carriage by disengaging the elongated sections of the strap from said third pair of guide members and exerting a pulling force on that short section to which said keeper member is secured, thereby causing said elongated sections to slidably move through said first and second pairs of guide members until the last-named short section is positioned beyond said cover by substantially half the length of one of said elongated sections and the other short section is positioned between each guide member of said first pair of guide members.

9. A carrying case comprising a front wall, a rear wall, a base, a cover, a first pair of metal strap guide members fixedly secured to said base, a second pair of leather strap guide members fixedly secured to said rear wall, a third pair of leather strap guide members detachably secured to said front wall, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of said first and second pairs of guide members and adapted to be detachably engaged by the other member of said third pair of guide members, each of said short sections being provided with a grip portion, said elongated sections being long enough to extend completely around the case through said guides so as to permit the grip portion of said short sections to be in engagement with one another, that grip portion forming part of the short section joining the extremities of the elongated sections slidably associated with said rear wall having detachably secured thereto a

keeper member adapted to encompass said grip portions, said carrying case being characterized by the fact that it is adapted for shoulder carriage by disengaging the elongated sections of the strap from said third pair of guide members and exerting a pulling force on that short section to which said keeper member is secured, thereby causing said elongated sections to slidably move through said first and second pairs of guide members until the last-named short section is positioned beyond said cover by substantially half the length of one of said elongated sections and the other short section is positioned between each guide member of said first pair of guide members.

10. A carrying case comprising a front wall, a rear wall, a base, a cover, a first pair of strap guide members fixedly secured to said base, a second pair of strap guide members fixedly secured to said front wall, a third pair of strap guide members detachably secured to said rear wall, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of said first and second pairs of guide members and adapted to be detachably engaged by the other member of said third pair of guide members, each of said short sections being provided with a grip portion, said elongated sections being long enough to extend completely around the case through said guides so as to permit the grip portion of said short sections to be in engagement with one another, that grip portion forming part of the short section joining the extremities of the elongated sections slidably associated with said front wall having detachably secured thereto a keeper member adapted to encompass said grip portions, said carrying case being characterized by the fact that it is adapted for shoulder carriage by disengaging the elongated sections of the strap from said third pair of guide members and exerting a pulling force on that short section to which said keeper member is secured, thereby causing said elongated sections to slidably move through said first and second pairs of guide members until the last-named short section is positioned beyond said cover by substantially half the length of one of said elongated sections and the other short section is positioned between each guide member of said first pair of guide members.

11. A carrying case comprising a front wall, a rear wall, a base, a cover, a first pair of metal strap guide members fixedly secured to said base, a second pair of leather strap guide members fixedly secured to said front wall, a third pair of leather strap guide members detachably secured to said rear wall, and an endless carrying strap comprising two elongated sections and two short sections, one of said elongated sections being slidably engaged by one member of each of said first and second pairs of guide members and adapted to be detachably engaged by one member of said third pair of guide members, the other of said elongated sections being slidably engaged by the other member of each of said first and second pairs of guide members and adapted to be detachably engaged by the other member of said third pair of guide members, each of said short sections being provided with a grip portion, said elongated sections being long enough to extend completely around the case through said guides so as to permit the grip portion of said short sections to be in engagement with one another, that grip portion forming part of the short section joining the extremities of the elongated sections slidably associated with said front wall having detachably secured thereto a keeper member adapted to encompass said grip portions, said carrying case being characterized by the fact that it is adapted for shoulder carriage by disengaging the elongated sections of the strap from said third pair of guide members and exerting

a pulling force on that short section to which said keeper member is secured, thereby causing said elongated sections to slidably move through said first and second pairs of guide members until the last-named short section is positioned beyond said cover by substantially half the length of one of said elongated sections and the other short section is positioned between each guide member of said first pair of guide members. 5
